UNITED STATES PATENT OFFICE

166,815

RECLINING CHAIR

Robert A. Maurer, East Palestine, Ohio, assignor
to The Kenmar Manufacturing Company, East
Palestine, Ohio, a corporation of Ohio

Application February 11, 1952, Serial No. 18,471

Term of patent 14 years

(Cl. D15—8)

To all whom it may concern:

Be it known that I, Robert A. Maurer, a citizen of the United States, residing at East Palestine, in the county of Columbiana and State of Ohio, have invented a new, original, and ornamental Design for a Reclining Chair, of which the following is a specification, reference being had to the accompanying drawing, forming a part thereof.

Figure 1 is a side view in perspective of a reclining chair, showing my new design;

Figure 2 is a front elevational view;

Figure 3 is a rear elevational view; and

Figure 4 is a side view in perspective showing the chair in reclining position.

I claim:

The ornamental design for a reclining chair, as shown.

ROBERT A. MAURER.
